APPARATUS FOR TREATING
HYDROCARBONS

Hans Magnus, Au, near Freiburg, Germany

Application March 12, 1929, Serial No. 346,319,
and in Germany March 10, 1928

2 Claims. (Cl. 196—132)

My invention refers to means for treating hydrocarbons and more especially to apparatus adapted for use in cracking heavy hydrocarbons at high temperature either in tubes or in a metal bath. It is an object of my invention to provide means for preventing the deposition of coke on the inner walls of the apparatus.

Hitherto, in order to limit the decomposition of carbon and the formation of coke, the raw material to be cracked was passed through the heating zone at high velocity, thereby providing that the carbon was deposited only in the succeeding zones of reaction, from which it could be removed more readily. However this mode of proceeding does not avoid local overheating and besides very high losses of pressure in the heating zone are experienced.

I avoid these drawbacks according to the present invention by regulating the temperature and keeping it constant by means of regulating devices, which control the passage of the oil through the heating zone in dependency from the temperature prevailing therein. As compared with the well known regulation of the temperature in the furnace, the regulation of the quantity and temperature of the oil entering the apparatus involves the advantage of temporary action, while if the heat of the furnace is regulated that part of the heat, which is accumulated in the brickwork, will still remain active for some time so that local overheating cannot be prevented.

I also succeed in preventing the deposition of carbon by reversing the direction of flow within the heating tubes, thereby creating eddies and causing the carbon to assume colloidal form, so that it cannot deposit in solid form.

In order to prevent overcracking I separate out the light oils produced during the cracking in a prevaporizer before the heated material is introduced into the reaction zone, in which it is subjected to final cracking during sufficient time. I thus succeed in preventing the petrol, which has already been formed in the preliminary cracking zone, from being decomposed in the final reaction zone.

In the drawings affixed to the specification and forming part thereof, apparatus embodying my invention are illustrated diagrammatically by way of example.

In the drawings

Fig. 1 is a diagram illustrating a cracking plant embodying my invention as a whole, while Figs. 2 and 3 are a longitudinal section and

end view, respectively, of the cracking tubes, and

Figs. 4 and 5 are vertical sections of two different forms of cracking arrangements including a metal bath.

Referring first to Fig. 1 of the drawings, 1 is a tank containing the raw oil and 2 is a pump which sucks the oil from tank 1 and forces it through a preheater 3 into the hot oil tank 4. 5 is a pump which forces the hot oil from the tank 4 into the tubes 6, in which the oil is heated to cracking temperature. A by-pass pipe 7 allows supplying the pump 5 directly with fresh oil. The proper mixture of hot and fresh oil is controlled by valves 8 and 9, which are influenced by a thermostat 10 arranged in the cracking zone in such manner that, if the temperature rises above a predetermined limit, the valve 9 is opened to admit more fresh oil, while, if necessary, valve 8 is partially closed to reduce the supply of hot oil. The thermostat may also be arranged to act through valve 11 onto the supply of fuel to the burner 12.

From the heating cracking zone the oil flows into the prevaporizer 13, in which it flows down on a corrugated surface 14 in order that the light petrol vapors be separated off, which escape through the safety valve 17 provided with the counter weight 18 and pipe 19 to the condensers 20, 21, where petrol can be withdrawn by means of the cocks 22, 23.

That part of the liquid, which is not vaporized in the vaporizer 13, flows from the collecting tank 15 through pump 16 and the open valve 24 (valve 25 being closed) through the heating and cracking zone 26 and through pipe 27 into the reaction cracking zone 28, where, owing to the reduced velocity of flow, the oil remains for some time as required by the cracking reaction. At 29 heavy residues, which have separated out may be withdrawn while the main portion of the liquid flows through pipe 30 and valve 31 into the vaporizer 32, in which spontaneous vaporization takes place. Any residues which do not undergo vaporization can be withdrawn through cock 33 or can be returned through valve 34 and pipe 35 to the pump 2 or may be fed into the burner.

The vapors from the vaporizer 32 pass into the condenser 36 for fractional condensation. Here the heaviest condensation products separate out in the bottom part and may be withdrawn at 37 or may be returned through valve 40 and pipe 43 to the pump 2. In the part of the condenser 36, which is air-cooled by means

of the ribs 44, lighter fractions separate out and can be withdrawn through cock 38 or returned to the pump through cock 41. In the uppermost part of the condenser, which is cooled by water, still lighter fractions can be withdrawn at 39 or returned at 42. Those vapors, which still escape through pipe 46, can be condensed in the petrol condensers 20, 21, through which passes cold cooling water entering through pipe 47 and escaping through coiled pipe 45, 48. Owing to this arrangement the cooling temperature in the uppermost part of condenser 36 is higher than the temperature in the condensers 20, 21.

Float valves 49, 50 in the prevaporizer 13 prevent liquid from entering the vapor pipe 19 if the level is too high, and vapor from entering the pump 16 if the level should be too low.

The cracking tubes 6 are illustrated on a larger scale in Figs. 2 and 3. The liquid is shown to enter the upper tube 6 in counter current to the heating gases and after having passed the inner tubes 51 has its direction of flow reversed near the end of the outer tube 52, passing through the connecting pipe 55 and entering the next following inner tube 51. Owing to this arrangement the transmission of heat from the heating gases to the oil takes place only while the oil is flowing with greater velocity through the outer tubes 52, while during the slower flow in the tubes 51 heat is transmitted only from the oil in the outer tube 52 to the oil in the inner tube 51. The stoppers 53, 54 can be withdrawn if it is desired to clean the tubes. The tubes 51 are positioned within the tubes 52 by means of ribs 56, which may have a helical form in order to effect a thorough mixture of the oil flowing between the ribs. The cross sectional areas are so chosen that the cross sectional area of the tubes 51 is more than one half of the cross sectional area of the tubes 52, thereby providing that the velocity of flow between the tubes is greater than that in the inner tubes 51.

In the modification illustrated in Fig. 4 the tubes 6 are replaced by a cracking vessel 58, which may be filled with a body of molten metal 59 serving to transmit heat to the oil. From the tank 4 in which the oil is preheated in the preheater 3, the pump 5 forces oil through valve 8 into the coil 57 arranged in the container 58. The thermostat 10 arranged in the molten metal 59 controls the feed of hot oil through valve 8 and of cold oil through valve 9 in such manner that if a predetermined temperature is overstepped the quantity of cold oil is increased while the quantity of hot oil is reduced.

In the modification illustrated in Fig. 5 a coil 63 supplied with fresh oil through pipe 60 and valve 61 is arranged in the cracking vessel 58. The oil passing through this coil is preheated therein and allowed to flow into the hot oil tank 4 from which it is forced by pump 5 through valve 62 into the container 58 to be subjected to cracking therein. The thermostat 10 controls the flow of the oil acting as a cooling medium through valve 61 and coil 63.

The hot oil tank 4 serves for equalizing the supply of preheated oil, which is required according to Figs. 1 and 4 by the circumstance that the withdrawal of hot oil varies in accordance with the regulation of valve 8 while according to Fig. 5 the provision of hot oil varies according to the regulation of valve 61.

Instead of regulating the cold and hot oil feeds it may also prove sufficient to regulate the passage of the oil across the cracking zone in such manner that the quantity of oil passing through is increased whenever the highest admissible temperature is overstepped.

The regulating valves are influenced by the thermostat by means of compressed air, pressure liquid or by electrical means in order that, although the thermostat only exerts very small forces, comparatively great forces can be exerted on the valves in order to enable them to overcome all resistances which may be offered by coke deposited within the valves.

Various changes may be made in the details disclosed in the foregoing specification without departing from the invention or sacrificing the advantages thereof.

I claim:—

1. An apparatus for treating hydrocarbons comprising an oil reservoir, a preheating coil, a cracking coil, a direct pipe leading from said reservoir to said cracking coil, another pipe leading from said reservoir to the preheating coil and from here into said direct pipe, valves in both pipes, a pump in the pipe between the juncture of the direct pipe with the pipe carrying the pre-heated oil and the cracking coil, and means for regulating the operative position of said valves in dependency upon the temperature in the cracking coil to increase the flow through said direct pipe when the temperature in the cracking coil rises, and to reduce the flow through said direct pipe if the temperature in the cracking coil drops.

2. An apparatus for treating hydrocarbons comprising an oil reservoir, a preheating coil, a cracking coil, a direct pipe leading from said reservoir to said cracking coil, another pipe leading from said reservoir to the preheating coil and from here into said direct pipe, valves in both pipes, a pump in the pipe between the juncture of the direct pipe with the pipe carrying the pre-heated oil and the cracking coil means for regulating the operative position of said valves in dependency upon the temperature in the cracking coil to increase the flow through said direct pipe when the temperature in the cracking coil rises, and to reduce the flow through said direct pipe if the temperature in the cracking coil drops, and a vessel for preheated material being inserted in said other pipe to the rear of said preheating coil, said vessel serving for balancing the difference between the supply of preheated oil to and the withdrawal of such oil from said cracking coil.

HANS MAGNUS.
